UNITED STATES PATENT OFFICE

JONATHAN PERKINS, OF LOS ANGELES, CALIFORNIA

TOY

Application filed August 20, 1928. Serial No. 300,644.

This invention relates to toys.

The general object of the invention is to provide an improved toy figure having a hemispherical supporting shell thereon and including means adapted to retain the figure in an upright position.

Another object of the invention is to provide a toy comprising a sphere adapted to support a hemispherical shell which may be made in the likeness of a character or may have a figure mounted thereon.

Other objects and the advantages of this invention will be apparent from the following description taken in connection with the accompanying drawings wherein:

Fig. 1 is an elevation of my improved toy showing the hemispherical shell made to represent a comic character.

Fig. 2 is an enlarged section through the device shown in Fig. 1.

Fig. 3 is a section taken on line 3—3 of Fig. 2.

Fig. 4 is a view similar to Fig. 1 showing a figure mounted on the hemispherical shell,

Fig. 5 is a section through a modified form of my device.

Referring to the drawings by reference characters I have indicated my improved toy generally at 10. As shown, my invention comprises a spherical member 12 which may be made in two parts suitably united, and a hemispherical shell 13, both of which are shown as made of papier-mâché, but it will be understood that they may be made of any other suitable material as desired.

The spherical member 12 is provided with a pair of oppositely disposed bearings 14 in which a shaft 15 is mounted. The bearings 14 may be of cardboard or other material secured to the member 12. As shown the outer ends of the shaft are upturned and are secured to the shell 13 by strips 16.

The shaft 15 has an enlarged collar 17 secured thereto adjacent the outside of the bearings 14 which prevent lateral movement of the shaft and the intermediate portion of the shaft is bent towards the bottom of the spherical member 12 as at 18 and has a

weighted member 19 arranged thereon at its lowermost point.

The weighted member 19 will at all times right the toy 10 so that the hemispherical shell 13 is free to move relative to the sphere 12 to cover the upper portion of the sphere no matter in what position the device may be set down.

A cord 20 may be attached to the shell and the device may thereby be drawn along, in which case the sphere 12 will rotate and the shell 13 will be retained in an upright position by the weight 19.

As shown in Fig. 1 the shell 13 is formed into a comic face having ears 21 and hair 22 secured thereto. The eye sockets are apertures 22 in the shell and a plurality of eye balls 24 are painted on the spherical member 12. As shown the eye balls 24 are placed around the member 12 in a staggered relation so that when the member 12 rotates the eye balls appear to move from side to side in the eye sockets.

In Fig. 4 I have shown the hemispherical shell 13 as completely covered by a fur-like material 25 which has a replica of a cat's head 26 attached thereto but it will be understood that any manner of figure or effigy may be placed on the shell.

In Fig. 5 I have shown a modification wherein a shell 30 is pivotally supported on a sphere 31 by a shaft 32. Oppositely disposed weighted members 33 are secured to the shell 30 below the axis of the shaft 32 and at right angles to the shaft as clearly shown. The weighted members 33 act the same as the weighted member 19 to retain the shell 30 in an upright position.

From the foregoing description it will be apparent that I have provided a novel toy which is simple in construction, inexpensive to manufacture, durable and efficient in use.

Having thus described my invention, I claim:

1. A toy comprising a spherical member and a hemispherical shell, a shaft, said shaft being supported by said sphere, the outer ends of said shaft being secured to said shell, a weighted member on said shaft, said weighted member being adapted to retain said shell in

an upright position, whereby said shell covers the upper portion of said spherical member, said shell being formed to represent a character and having parts of said character thereon, other parts of said character being cut therefrom, still other parts of said character being on said sphere and adapted to coact with some of said parts on said shell.

2. A toy comprising a spherical member and a hemispherical shell, oppositely disposed bearings in said sphere, a shaft, said shaft being supported in said bearings, the outer ends of said shaft being secured to said shell and the intermediate portion of said shaft being bent towards the bottom of said sphere, a weighted member on said shaft adjacent its lowermost point, said weighted member being adapted to retain said shell in an upright position whereby said shell covers the upper portion of said spherical member, an enlarged flange on said shaft adjacent the outside of each of said bearings, said flanges being adapted to prevent lateral movement of said shaft.

25 3. A toy comprising a spherical member and a hemispherical shell, oppositely disposed bearings in said sphere, a shaft, said shaft being supported in said bearings, the outer ends of said shaft being secured to said shell and the intermediate portion of said shaft being bent towards the bottom of said sphere, a weighted member on said shaft adjacent its lowermost point, said weighted member being adapted to retain said shell in an upright position whereby said shell covers the upper portion of said spherical member, an enlarged flange on said shaft adjacent the outside of each of said bearings, said flanges being adapted to prevent lateral movement of said shaft, a pair of horizontally aligned apertures in said shell and a plurality of objects on said sphere so arranged that when said sphere is rotated said objects appear to move in said apertures.

45 4. A toy comprising an inner spherical member and an outer hemispherical shell, a shaft having its ends connected to diametrically opposite parts of the interior of said shell and passing through said sphere and means supported by said connecting means to maintain said shell in a position covering the upper half of said sphere.

5. A toy comprising a rotatable inner member serving as a support for the toy and an outer member of the same contour as the inner member and within which said inner member moves, a pair of apertures in said outer member and a plurality of objects on said inner member and movable across said apertures when the member is rolled.

6. A toy comprising a support in the form of a spherical member and a hemispherical shell movable on said spherical member, a pair of horizontally aligned apertures in said shell and a plurality of objects on said

sphere, said objects being arranged so that when said sphere is rolled along said objects appear to move in said apertures.

In testimony whereof I hereunto affix my signature.

JONATHAN PERKINS.
